UNITED STATES PATENT OFFICE

147,028

DESIGN FOR A BOTTLE CASE

Jefferson P. Waldrop, Arlington, Va.

Application September 20, 1945, Serial No. 122,214

Term of patent 14 years

(Cl. D58—13)

To all whom it may concern:

Be it known that I, Jefferson P. Waldrop, a citizen of the United States, residing at Arlington, in the county of Arlington and State of Virginia, have invented a new, original, and ornamental Design for a Bottle Case, of which the following is a specification, reference being had to the accompanying drawing, forming a part thereof.

The single figure is a perspective view of my new design for a bottle case.

I claim:

The ornamental design for a bottle case, as shown.

JEFFERSON P. WALDROP.
